 Instruction insert for Wilson's ProFeel Vibration Dampening Device, 1988.

Primary Examiner—Ted Shooman
Assistant Examiner—Mitchell I. Siegel

[57]**CLAIM**

The ornamental design for a vibration dampener for a game racquet, as shown and described.

DESCRIPTION

FIG. 1 is a perspective view of a vibration dampener for a

game racket showing our new design, the broken line showing of a fragmented racket is for illustrative purposes only and forms no part of the claimed design; FIG. 2 is a view of one end of the vibration dampener for a game racquet, the other end view being a mirror image thereof; FIG. 3 is a top plan view of the vibration dampener for a game racquet;

FIG. 4 is a front elevational view of the vibration dampener for a game racquet; FIG. 5 is a bottom plan view of the vibration dampener for a game racquet; and, FIG. 6 is a rear elevational view of the vibration dampener for a game racquet.
